(57) **CLAIM**

The ornamental design for a bottle, substantially as shown and described.

DESCRIPTION

FIG. 1 is a perspective view of a bottle showing my new design;

FIG. 2 is a front view of the bottle shown in FIG. 1;

FIG. 3 is a rear view of the bottle shown in FIG. 1;

FIG. 4 is a side view of the bottle shown in FIG. 1, the other side being a mirror image thereof;

FIG. 5 is a top plan view of the bottle shown in FIG. 1; and,
FIG. 6 is a bottom plan view of the bottle shown in FIG. 1.

The broken lines are included for the purpose of illustrating visible, internal structure that forms no part of the claimed design. The appearance within the unshaded region of FIG. 5 forms no part of the claimed design, it being understood that the solid line boundary thereof is part of the claim.
